UNITED STATES PATENT OFFICE

126,052

DESIGN FOR A COSMETICIAN'S TRAY

William B. Petzold, Pittsfield, Mass., assignor to General Electric Company, a corporation of
New York

Application December 6, 1940, Serial No. 97,115

Term of patent 14 years

To all whom it may concern:

Be it known that I, William B. Petzold, a citizen of the United States, residing at Pittsfield, in the county of Berkshire, Commonwealth of Massachusetts, have invented a new, original, and ornamental Design for a Cosmetician's Tray, of which the following is a specification, reference being had to the accompanying drawing, forming a part thereof.

In said drawing:

Fig. 1 is a front perspective view of a cosmetician's tray, showing my new design.

Fig. 2 is a front perspective view of the cosmetician's tray, to a somewhat reduced scale, and showing an inner compartment rotated to open position.

The rear side of the tray is identical with the front side shown in Fig. 1.

I claim:

The ornamental design for a cosmetician's tray, as shown.

WILLIAM B. PETZOLD.
